UNITED STATES PATENT OFFICE.

JAMES K. LANNING, OF FALL RIVER, MASSACHUSETTS.

HALF LAP FOR COMBING TEXTILE FIBERS.

Application filed March 17, 1926. Serial No. 95,259.

This invention relates to half-laps for textile fibers and is in the nature of an improvement upon the type of half-flap now known as the "Wood" half-lap which is the invention 5 of William Wood of Fall River.

The object of the invention is to provide a simple construction for the comb-bar or needle-bar, each of which carries a row of properly spaced projecting needle points, 10 which shall be durable in construction and not subject to the formation of any minute crevices or cracks for the lodgment of lint, while locating the needle points in such relation to the surface of the slotted matrix or 15 bed, in which the comb-bars are mounted, as to avoid any accumulation of lint in the angle between the bed of the half-lap and the overhanging row of needle points.

To this end the invention comprises essentially 20 an elongated flat comb-bar proportioned to snugly fit in and fill its receiving slot in the bed of the half-lap, said bar being slotted from its outer edge inwardly intermediate of the front and rear faces to snugly 25 receive the butt ends of a row of needles whose points project outwardly beyond the outer edge of the bar so as to afford complete reinforcement and support for the needle, both front and back, and prevent the 30 formation of crevices due to flaking of the solder when the needles are applied to the forward face of the bar. A further feature of the invention resides in the construction of the comb-bar adjacent to the needle points 35 so that no angle capable of retaining lint is formed in front of the needles, while at the same time the clearing brushes are given complete access to the interstices between the needles for keeping the half-lap entirely 40 clear of lint.

These and other features of the invention will be explained in the following specification and will be defined in the claims here-to annexed.

45 In the accompanying drawings I have shown a construction and arrangement of comb-bar mounted in the half-lap embodying the principles of this invention, in which:

50 Figure 1 is an end elevation of the half-lap bed mounted on its rotating sleeve.

Figure 2 is a detail view of one end portion of the half-lap on the sectional plane 2-2 of Figure 1 to show the comb-bar in 55 front elevation as it is seated in its supporting slot in the bed.

In the practice of this invention as illustrated in the drawings, the arcuate half-lap bed 2 is provided with front and rear extensions 2^a and 2^b by which the half-lap bed is 60 securely fastened to the supporting sleeve 1, by means of suitable fastening screws in a well known manner.

This half-lap bed 2 is formed with a series of longitudinal slots extending from end to 65 end and radiating from the axis at progressively increasing angles to the intersecting radii of the half-lap bed to give an increasingly sharp edge from the rear of the half-lap to the front, with reference to the direction of location indicated by the arrow in Figure 1.

The comb-bar itself comprises a longitudinal flat bar 3 dimensioned to fit snugly into its longitudinal slot and substantially thicker 75 than the comb-bars commonly used in the Wood half-lap. This bar is of sufficient depth from its inner to its outer edge to seat snugly in the bottom of the slot and project outward slightly beyond the peripheral surface of the bed 2, which surface will usually be of cylindrical contour.

Intermediate of the front and rear sides of the flat comb-bar 3, there is formed a longitudinal slot of substantial depth of a 85 width to snugly receive the butt ends of the row of needles 4 inserted therein. The outer corners of the comb-bars, that would otherwise project beyond the surface of the bed, are beveled off in front of and to the rear 90 of the needles so that the beveled surface exactly meets the peripheral surface of the bed 2, as shown at 3^b. Preferably the rear corners are beveled off in similar fashion and, owing to the inclination or obliquity of 95 the bars with relation to the radii of the half-lap, the rear faces will have a longer bevel than the front faces.

The advantages of this construction are found in the fact that equally with the Wood 100 form of half-lap it prevents objectionable accumulation of lint beneath the overhanging points of the needles, affords the best possible exposure of the entire projecting portions of the needles to the action of the 105 brushes, while at the same time providing a very strong and firm support for the needles and avoiding the formation of minute cracks or crevices that sometimes result from the flaking of the solder on the front face 110 of the bar when the needles are soldered to the front face, according to previous prac-

5 tice. It is also possible to make an exact and accurate fit between the comb-bar and the edges of the receiving slot so that there is no opportunity for the lodgment and accumulation of lint, which always seriously 10 impairs the efficiency of the half-lap and results in inferior work.

10 The comb-bars 3 are securely held to their seat in the slots by means of endwise fastening screws 5 engaging the inner side of a notch formed in the end of the comb-bar, as 15 shown at 3^a.

What I claim is:

15 1. In a half-lap for combing fibers, the combination with an arcuate bed having a cylindrical peripheral surface with a series of longitudinal inwardly extending slots formed therein, a series of comb-bars fitted 20 snugly into said slots each with its outer edge portion projecting somewhat beyond said peripheral surface, such projecting portion being beveled at front and rear to leave opposite inclined faces outside the peripheral face, and a row of needles imbedded in 25 said bar between the beveled faces with their points projecting outward.

2. A comb-bar for a half-lap embracing a flat longitudinal bar adapted to be snugly

fitted into a receiving slot in the half-lap bed, said bar having a longitudinal slot 30 formed in its outer face intermediate of its front and rear faces, a row of needles secured in said slot with their points projecting outward, the corner of said bar in front of the needles being beveled off to approximately meet the adjacent edge of its slot when the bar is inserted.

3. A comb-bar for a half-lap embracing in its construction a longitudinal bar with flat forward and rear faces adapted to be 40 snugly inserted in a corresponding slot in the bed of a half-lap, said bar being provided with a longitudinal channel intermediate of its front and rear faces and extending inwardly from its outer face, a row of needles 45 secured side by side in said channel with their points projecting outwardly therefrom, the front and rear outer corners of said bar being oppositely beveled from the line of needles to a point corresponding with the 50 adjacent edges of the receiving slot in the half-lap bed, substantially as described.

In witness whereof, I have subscribed the above specification.

JAMES K. LANNING.
